UNITED STATES PATENT OFFICE

HENRY WEBER, OF OAKLAND, CALIFORNIA

BATTERY POST CONNECTION

Application filed January 26, 1929. Serial No. 335,285.

The invention relates to connections for electric terminal posts, and particularly to a means for preventing corrosion at the connections for the terminal posts of storage batteries.

An object of the invention is to provide a connection for a storage battery post, or other electrical terminal post, which itself provides a reservoir for a corrosion-preventing substance for the connection provided by it.

Another object of the invention is to provide means whereby the corrosion-preventing substance is arranged to be automatically supplied from the reservoir to the parts to be protected.

A further object of the invention is to provide for a renewal of a charge of the corrosion-preventing substance without requiring a detachment of the connector.

Yet another object of the invention is to incorporate the before mentioned features in a unitary connector.

The invention possesses other objects and features of advantage, some of which, with the foregoing, will be set forth in the following description of a preferred form of the invention which is illustrated in the accompanying drawings, in which:

Figure 1 is an elevation showing the connector operatively mounted on the terminal post of a storage battery, only a fragment of the battery being shown.

Figure 2 is a plan view of the installation of Figure 1.

Figure 3 is a fragmentary sectional view taken on the line 3-3 in Figure 2.

Figure 4 is a sectional view taken on the line 4-4 in Figure 3, a portion of a packing wick being broken away for clarity.

As is well known, electrical connections which are exposed to the action of the fumes of acid or other chemicals must be protected to prevent their corrosion and the formation of corrosion products thereon. This is particularly true in the case of connections for lead storage batteries in which sulphuric acid is used as an electrolyte and from which acid and acid fumes escape to corrode the connections unless the latter are protected by such means as an acid resistant coating. Ac-

cordingly, it has heretofore been the general custom to protect such connection portions as are subject to corrosion by coating the same with a suitable acid resistant preparation, substances formed of or containing petroleum greases or animal fats being most commonly used for the purpose. Such coatings must, however, be periodically renewed, as they dry out through the acquisition of dust and are also melted or brushed from the members they protect, and the present invention accordingly provides for a constant and automatic maintenance of a protective coating on the connections by providing in a connector member thereof a reservoir for a supply of the coating substance and means for effecting a distribution of the substance to the parts to be protected.

As particularly disclosed, the invention is incorporated in the structure of a connector 6, which connector is arranged to be fixed to the end of a conductor or cable 7 and to be removably attached to a terminal post 8 of a storage battery 9. While the post 8 is usually formed of lead, which is acid resistant, the connector 6 is formed of some other and stronger metal than lead, which other metals are subject to the corrosive action of the acid. The connector 6 is provided centrally thereof with an opening 11 extending as an eye through the connector between opposite faces 12 thereof and arranged to freely receive the battery post 8 which, in the present instance, is of circular cross-section. A set-screw 13 is threadedly engaged in the connector 6 for projection into the opening 11 radially thereof for a set engagement against the post 8 in the eye opening. The opening 11 is of generally circular cross-section, and since its radius of curvature exceeds that of the post, a setting of the set-screw 13 against the post 8 will effect a two-point electrical contact with the post at diametrically opposite sides thereof, thereby avoiding the necessity of a tight fit of the post in the opening 11 and insuring the ready removability of the connector. The electrical contacts provided are also, of course, positive ones.

For securing the connector 6 to the cable 7, the former is provided with a socket 14 in

which the cable extremity is arranged to be inserted and fixed as by soldering.

Preferably, and as shown, the axes of the set-screw 13 and socket 14 are aligned diametrically of the opening 11 and these elements lie at opposite sides of said opening.

A depression 15 in the form of an annular groove is provided in the bore 16 of the eye opening 11, said groove lying intermediate the bore ends and being arranged to receive the set-screw 13 therethrough. The width of the groove 15 axially of the bore preferably somewhat exceeds the diameter of the set-screw for a reason to be hereinafter brought out. Mounted in the groove 15 in fitted engagement therein is an annular packing ring 17 formed of a liquid pervious material such as felt and having the general properties of a wick; since the wick properties of the ring 17 are all-important, as will appear, said member is hereinafter conveniently referred to as a wick. The central perforation of the wick 17 is smaller than the post 8 whereby the wick is arranged to forcibly engage about the post when the post is engaged in the connector. The set-screw 13 is arranged to extend through the wick 17 for engaging the post whereby its post contacting end is enclosed in the wick material. When the set-screw 13 is operative the post 8 is, of course, forcibly engaged with the bore 16 at one or both sides of the wick.

It will now be noted that the wick 17 is arranged to contain a charge of a fluid or semi-fluid corrosion-preventing substance 18 whereby the post engaging set-screw portion and the post thereat are enclosed in said substance and corrosion at the point of contact is positively prevented. The substance 18 it is noted, must also possess the property of capillary movement through the wick and along a metallic surface, it being noted that substances containing coal-oil are among those which possess both of these properties as well as being acid resistant. In this manner, the presence of the corrosion-preventing substance is not only arranged to be maintained at the set-screw contact points, but said substance will actually travel along the post and connector bore surfaces to maintain the same in a coated condition at a distance from the wick and including the point of contact of the post with the connector bore. It will thus be clear that the wick action of the ring or wick 17 is essential for maintaining a supply of the corrosion preventing substance at the contact points and on exposed surfaces of the connector. It is further noted that the creeping travel of the substance with which the wick is charged may readily extend over the entire connector surface, the set-screw, and adjacent cable portions, particularly if said surfaces be first coated with said substance, such being indicated in a necessarily

exaggerated degree in Figures 3 and 4 of the drawings.

In view of the foregoing, it is seen that the groove 15 constitutes, in effect, a reservoir for the corrosion-preventing substance 18, from which reservoir the wick 17 is operative to assist in distributing said substance over the post and connector surfaces entirely by capillarity. The present connector is particularly shaped to facilitate this distribution, being designed as generally elliptical in plan to provide the mounting for the set-screw 13 and the cable receiving socket 14 at opposite ends thereof. The distance between the connector faces 12 is also made as small as is practicable. In this manner, the connector is arranged to contain a minimum of surface as well as material, and its surface portions are relatively close to the reservoir for receiving the coating substance therefrom. It is noted that the bore 16 is arranged to receive either truly cylindrical or tapered posts for securing therein by means of the set-screw 13, the present post 8 being of the former type. It is clear that the post, also receives a coating of the substance 18, such not being needed, however, unless the post is of other material than lead.

Since a charge of the corrosion-preventing substance 18 will gradually be dissipated through the capillary spreading action previously described, means are preferably provided for permitting a recharging of the reservoir 15 and wick 17 without necessitating a dismounting of the connector from the post. If the post 8 is considerably smaller than the connector bore 16, a space will be left along the post and above the wick through which recharging material may be supplied to the reservoir and wick; but when, as is shown and preferred, the post is but little smaller than the bore, a special provision must be made for permitting a recharging of the reservoir groove 15. Accordingly, one or more axial slots 19 are provided in the bore 16, each slot extending from the groove 15 to a connector face 12 and cooperating with the opposed post surface to provide a conduit for the insertion of material for recharging the reservoir and wick. A plurality of the recharging conduits is preferably provided, and as shown, the bore 16 is axially slotted for the full length and at diametrically opposed sides thereof to provide four slots 19 whereby the connector is reversely mountable on the post to always provide two slots 19 for refilling the reservoir from above by gravity. Preferably, the plane of the slots 19 is perpendicular to the set-screw axis. If the recharging substance is not normally free flowing, it would be heated to increase its fluidity for recharging. The upper slots 19 may, of course, contain an excess charge portion for distribution in the indicated manner.

From the foregoing description taken in connection with the accompanying drawings, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative, and that such changes may be made, when desired, as fall within the scope of the appended claims.

Having thus described my invention, I claim as new and desire to secure by Letters Patent of the United States the following:

1. In a device for connecting a conductor to a terminal post, a body member providing a socket for the fixed reception of an extremity of the conductor and an opening for the free reception of said post, a set-screw mounted in said body for engagement against a post in the opening, an annular depression in the bore of said opening, an annular wick member disposed in said depression and arranged to resiliently engage about the post, and a corrosion-preventing substance impregnating said wick member.

2. In a connector for mounting on a cylindrical terminal post, an eye providing a generally cylindrical bore for closely but freely receiving said post, means for releasably fixing said post in said bore, a depression in said bore intermediate the ends thereof, a wick member in said depression for resiliently engaging the post, a corrosion-preventing substance in said depression and impregnating said wick member, and a groove in said bore extending axially from said depression to an end of the bore whereby a passage is defined along the said bore for use in renewing the charge of said substance in the depression and wick member.

3. In a connector for mounting on a terminal post, an eye providing a bore for freely receiving said post, means for releasably fixing said post in said bore, a depression in said bore intermediate the ends thereof, a corrosion-preventing substance in said depression, and a groove in said bore extending axially from said depression to an end of the bore whereby a passage is defined along the said bore for use in renewing the charge of said substance in the depression.

55 In testimony whereof, I affix my signature.
HENRY WEBER.
